ORDNANCE

Félix Frédéric Ruau, Deptford, London, England,
assignor to Molins Machine Company Limited,
London, England

Application May 10, 1944, Serial No. 534,905
In Great Britain May 10, 1943

2 Claims. (Cl. 89—24)

1

This invention concerns improvements in or relating to breech-mechanism for ordnance and in particular to breech-mechanism of the type in which the breech-block slides transversely to the axis of the bore and is held open against the action of springs by retaining catches or extractors which are actuated by the rim of a round when the latter has completely entered the breech-chamber to release the breech-block. Such breech-blocks have a substantially concave surface for guiding a round in ramming and a chamfer or bevel extending from said surface to the inner surface of the breech-block (that is to say the surface which co-operates with the chamber face), so that if the round is not seated as the block is closed the chamfer or bevel will engage the base of the round and push it home. Such breech-mechanism, which is known as semi-automatic breech-mechanism, is referred to hereinafter as "breech-mechanism of the type described," and the term when used herein is to be considered as including cases in which the rounds are automatically fed and automatically fired.

It has been found that, when guns having breech-mechanisms of the type described have been fitted with automatic feeding and ramming mechanism, occasionally the breech, on closing, has become jammed by reason of the round being not completely home. It has also been found that this fault has been caused by rebounding of the round as it strikes the chamber face beyond the edge of the breech-block where the bevel terminates, due it is believed, to the speed at which the round is rammed into the breech-chamber. Some breech-blocks of the type described slide horizontally and some slide vertically and it will be appreciated that the one is the equivalent of the other so far as the present invention is concerned.

Jams of the nature described are prevented, according to the present invention, by the provision in breech-mechanism of the type described, of a stop at or in the region of the inner concave edge of the breech-block, said stop being adapted to move behind a round after the latter has been fully rammed into the breech-chamber so as to limit rebounding of the round from the breech-chamber the position of the stop being such that the base of a round striking the stop on rebounding will be engaged and pushed into the breech-chamber by the chamfer of the breech-block as the latter closes, wherein the stop is of substantial width and its top surface is of generally

10

curved shape to constitute a guide to help to centre the nose of a round.

A further difficulty has been found to arise due to the employment of a certain kind of round which is used to a considerable extent at the present time, and which has at least one circumferential edge, such as an outstanding edge where the case overlaps the projectile and the edge formed by the projectile and its flat nose. Rounds of this kind will be referred to herein and in the appended claims as "rounds as specified." Although the edge of the rim at the base of such a round constitutes a circumferential edge, the expression "circumferential edge" when used in connection with a round as specified, does not include this edge of the rim, but only such edges as are to be inserted in the breech so as to pass the chamber-edge as defined hereinafter. When ramming rounds of the kind specified, it sometimes happens that the edge of the flat nose of the round, or the outstanding edge of the case where it overlaps the projectile, catches against an edge of the breech-chamber, thus preventing the round from being properly rammed home and causing a jam. In order to prevent jams of this nature, the stop may be so arranged (e. g. by providing a spring of suitable strength) that as a round is being rammed, the stop is held in its outer position to act to guide any circumferential edge of a round as specified clear of the chamber-edge but is depressed when the base of a round passes over it.

The stop may be wedge-shaped in the sense that it provides a lead for a round being rammed.

35 A breech-block made in accordance with the present invention will now be described by way of example with reference to the accompanying drawing in which:

Fig. 1 is a sectional elevation of part of a breech-block showing the round-retaining-device and its relation to the breech-chamber when the breech-block is held in the open position after having moved up from its lowermost position;

Fig. 2 is a front elevation of the breech-block 40 shown in Fig. 1; and

Fig. 3 is a diagrammatic view of an example of a round as specified.

Like reference numerals refer to like parts throughout the several figures of the drawing.

45 50 The breech-block 5 is arranged to slide vertically upwards to close the breech 4, part of which only is shown. The usual chamfer-surface provided at the upper part 50 of the inner surface of the breech-block which co-operates with the chamber face C—F, can be clearly seen from the

2

drawing. The usual breech-retaining-members which are moved in to release the breech-block when engaged by the rim of a round, are not shown, as being unnecessary for the understanding of the invention.

Rebounding of the round as it strikes the chamber-face is prevented by a stop or retainer-shoe 353. The retainer shoe 353 has a curved upper surface whose curvature substantially corresponds to that of the concave surface of the breech-block. This retainer-shoe 353 is, as can be seen from Figure 2, of considerable width so that it can during the initial part of the ramming stroke act as a guide and help to centre the nose of the round and thus perform part of the function of the curved top of the breech-block in addition to performing its subsequent function of trapping the round.

The retainer-shoe 353 also acts as a guide to centre the nose of a round by reason of the fact that it remains in its upward or outer position while the nose of a round is passing over it and is not depressed until substantially the whole of the round has entered the breech-chamber. For this purpose the retainer-shoe is provided with a strong compression-spring 408, which is already partly compressed when the shoe is fully up, and is strong enough to resist further compression except by a stronger force than that provided by the weight alone of a round. The purpose of this arrangement is to enable rounds as specified to be rammed without jamming. An example of a round as specified is shown diagrammatically in Figure 3. The round shown has, as can be seen, a circumferential edge 45 where the case overlaps the projectile and also another circumferential edge 440 formed by the projectile and its flat nose 44. When rounds of this kind are rammed into the breech-chamber, it sometimes happens that the edge 440, or the edge 45, catches against the edge 116 of the breech-chamber recess 16 with the result that the round is unable to move into the breech-chamber in the proper manner. The recess 16 is adapted to receive the rim 115 of the round.

In the example described the chamber-edge 116 is formed by the chamber and the recess 16, but in cases where the rounds have no rim at the base, the recess 16 will not be present so that the chamber-edge will in such cases be the edge formed by the chamber and the chamber-face. For convenience the expression chamber-edge is used herein and in the appended claims, and has the meaning given above.

By the provision of the curved retainer-shoe 353, which by reason of its strong spring is kept in its outer position while the round is being introduced into the breech-chamber, the circumferential edges 440 and 45 can be kept out of contact with the chamber-edge.

As the round moves completely into the breech-chamber the rim of the round as it passes over the retainer-shoe forces the latter down, and the shoe springs up again after the rim has passed it to trap the round should it tend to rebound.

The arrangement of the retainer-shoe 353 on

the breech-block is such that the shoe is provided with a spring-barrel 106 slidable in a hole 107 in the breech-block 5 and containing the compression-spring 108, slight play existing between said barrel and shoe to provide for their relative movements. The spring-barrel may be depressed by inserting a small rod or tool through the hole 116 in the shoe, when the shoe can be slipped out. The heel of the shoe fits into the recess 9 in the breech-block.

The shoe 353 is provided with two lugs 11, one at each side, which are arranged to fit into recesses 12 in the breech-block. The purpose of this arrangement is to limit the upward movement of the shoe by engagement of the lugs 11 with the upper walls 13 of the recesses.

The retainer shoe as shown in Figure 1, is wedge-shaped in the sense that it slopes upwardly towards the breech-chamber whereby a round can slide forwardly over it, without the rim being caught, but rebounding is prevented by engagement of the round against the steep face of the retainer shoe.

The breech-block is so arranged relatively to the breech-chamber when the former is held in the open position that the top of the retainer-shoe when fully up is in a position behind the recess in the breech-chamber which accommodates the rim of the cartridge.

What I claim as my invention and desire to secure by Letters Patent is:

1. In breech-mechanism of the type described, in combination with a breech-chamber and a breech-block slideable transversely of the axis of the bore of said chamber and in contact with the face thereof, said block having a concave surface for guiding a round into the breech-chamber and a chamfered edge on said surface contiguous to the chamber face, a stop movably mounted on said block adjacent the chamfered edge thereof, means yieldingly urging said stop above the concave surface of the breech-block into a position behind a round after the latter has been fully rammed into the breech-chamber so as to limit rebounding of the round from the breech-chamber, said stop being so constructed and arranged relative to the chamfered edge of the breech-block that the base of a round striking the stop on rebounding will be engaged and pushed into the breech-chamber by said chamfered edge as the breech-block closes, said stop being relatively wide and having a concave upper surface constituting a guide to help to centre the nose of a round entering the breech-chamber.

2. Breech-mechanism as claimed in claim 1, in which said yieldingly urging means maintains the stop in a position such that, when a round is being rammed, at least a portion of the upper surface of said stop is above the edge of the breech-chamber so as to guide any circumferential edge of a round clear of the chamber edge, said yieldingly urging means yielding to permit depression of the stop when the base of a round passes over it.

FÉLIX FRÉDÉRIC RUAU.
